UNITED STATES PATENT OFFICE.

ROY J. MILLER, OF COLUMBUS, WISCONSIN.

DISK-RECORD FILE.

1,412,537.

Specification of Letters Patent. Patented Apr. 11, 1922.

Application filed March 29, 1921. Serial No. 456,566.

To all whom it may concern:

Be it known that I, ROY J. MILLER, a citizen of the United States, and resident of Columbus, in the county of Columbia and State of Wisconsin, have invented certain new and useful Improvements in Disk-Record Files; and I do hereby declare that the following is a full, clear, and exact description thereof.

10 The invention relates to improvements in phonograph cabinets generally, and more particularly to a type thereof embodying a file compartment, or compartments, for the reception of a supply of sound records to be played on the mechanism of the same.

The principal object of the invention is to provide for a phonograph cabinet of the character mentioned, and one embodying a disk record filing means, whereby to facilitate the selection and removal of a desired record without necessitating the removal or displacement of the other of the records as may be associated with the selected or desired record within the same compartment of the cabinet.

Another object of the invention is to provide for a cabinet of the class set forth, and one embodying a disk record compartment or compartments, whereby all of the records of a particular compartment are presented to full view for the selection of a desired record, from among a number of such records within the compartment, in a quick and easy manner, and free from the usual tiresome effort and annoyance now obtaining in the known methods and arrangements of filing and selecting such records.

A further object of the invention is to provide one or more disk record-receiving compartments within a phonograph cabinet wherein the records are placed within the same for subsequent selection and use and in a manner whereby to dispense with the necessity of associating therewith any of the usual forms of index systems, such as are extremely objectionable in that they necessitate an expenditure of time and effort in the making of proper entries for the identification and location of the records in addition to that required for the actual selection and removal of the particular or desired record from among a number of the records within a compartment or compartments of the cabinet.

55 With the foregoing and other objects in view, the invention resides in the certain

novel and useful construction and arrangement of parts as will be hereinafter more fully described, set forth in the appended claim and illustrated in the accompanying drawing, in which:

Figure 1 is a fragmentary vertical section of a phonograph cabinet showing the preferred embodiment of the invention as applied thereto, the latter being shown in side elevation and partly in section,

Figure 2 is a fragmentary vertical section transversely of the cabinet and a record compartment thereof, and

Figure 3 is a front elevation of a cabinet of conventional form generally, but showing the appearance of the same with the preferred arrangement of the drawer record compartments therewith.

Referring to the drawing, wherein similar characters of reference designate corresponding parts in the several views thereof, the numeral 10 indicates generally a phonograph cabinet of conventional form, 11 and 12 the front and rear walls, 13 and 14 the opposite side walls thereof, respectively, and 15 a centrally disposed partition wall extending parallel to the opposite side walls 13 and 14 and connecting the front and rear walls 11 and 12, when a cabinet is to be provided with two of the compartments *a* and *b*, one parallel to the other in a common plane horizontally thereof as shown in Figure 3.

Each drawer compartment *a* and *b* consists of a bottom wall 16, opposite side walls 17 and 18, a rear wall 19 of equal height to that of the side walls 17 and 18, and a front wall 20 of a substantially greater height than that of the side and rear walls. Each of these drawers is slidably mounted within the cabinet, and slidable in and out of an opening 21 formed in the front wall 11. The bottom wall 16 being slidable in relatively close relation to the lower edge of the opening 21, and the side walls 17 and 18 in spaced relation with respect to the opposed side walls of the cabinet, said side walls, 17 and 18, being of a height substantially less than that of the vertical walls of the said opening 21, while the front wall 20 is of an area whereby to entirely close the opening complementary thereto, when the drawers are inward of the cabinet.

For admitting of the desired sliding movements of the drawers *a* and *b*, each has associated therewith a pair of trackways, one at

each side of the drawer, and these trackways consist of pairs of bars 22 and 23, preferably in the form of suitable lengths of substantially L-shaped angle iron arranged in reversed order to provide channelways therebetween to receive the complementary flanges or portions of similarly shaped bars 24 and 25, respectively, secured on the outer faces of the opposite side walls 17 and 18 of a drawer, a suitable knob or handle 26 being provided on the front faces of each of the drawers to facilitate the opening and closing movements of the same.

Extending through each of the drawers *a* and *b* is a pair of screw rods or shafts 27, which have their opposite ends journaled in the front and rear walls 20 and 19 thereof, and the rods or shafts of each pair are spaced apart to either side of the longitudinal center of the drawer and lie in close proximity to the adjacent portions of the side and bottom walls of the same. The forward ends of the rods or shafts 27 are secured in the bores of operating sleeves or members 28 which are journaled in the front wall 20 and have their outer ends formed to provide knurled head portions 29 by means of which they may be conveniently grasped by the fingers for imparting turning movements to the rods or shafts for the forward and rearward adjustment within the drawer of a follower 30, which, in turn, is provided with bearing members or sleeves 31 passed through the lower portion of the same and arranged in threaded engagement with the rods or shafts 27. Extending forwardly from the top edge of the frame or member 30 of the follower is a downwardly inclined follower plate or member 32 against the forward face of which is to be normally supported in correspondingly inclined relation a series of record holders 33 which have circular openings 34 formed at their lower opposite corners suitably engaged for free sliding movement on the rods or shafts 27. These holders 33 are each formed of a relatively stiff material to provide envelopes or pockets adapted to enclose the lower major portion of a disk record, and have their front walls provided with circular openings 35 disposed centrally thereof whereby to register with and expose to view therethrough the usual circular and concentrically arranged identification or name labels of ordinary forms of disk records.

In the use of the drawer compartments constructed and arranged in accordance with the invention, a suitable number of the record holders 33 is positioned on the rods or shafts 27 within each drawer *a* and *b*, and disk records are inserted in position therein, one to each of the holders, and with the labels of the records showing through the circular openings 35 whereby they may be

viewed from the forward end of each drawer. After the holders have been filled, the same are inclined rearwardly so as to lie flat one in contacting relation with respect to the other and against the follower plate 32, in which position the uppermost edge portions of the records will be free to pass under the top edge of the opening 21 of the cabinet wall, when the drawer, or drawers are moved inwardly and outwardly of the cabinet. With the drawer or drawers positioned within the cabinet and it is desired to select a record, the same are pulled outward of the cabinet, the outward movement being limited by means of suitable abutments or stops 36 carried on the top edge of the follower frame 30 if desired, and the record labels are successively viewed through the circular openings 35 in the holders or pockets 33, by raising the holders or pockets to vertical position forwardly of the drawer in which the particular or desired record is to be located, and, after the selected record has been removed from its pocket, the holders are again inclined rearwardly and the drawer can be moved to closed position. It is to be noted that the looseness of engagement of the openings 34 with the rods or shafts 27 allows for comparatively free movement of the record holders 33 to and from inclined position for the purposes indicated.

It is well understood that, while the invention has been described and illustrated herein in very specific terms of detail construction and arrangement, various changes in the several parts of the same, or the manner of their assemblage and application may be resorted to without departing from the spirit and scope thereof.

Having thus fully described my invention, what I claim as new, and desire to secure by Letters Patent, is:—

The combination with a phonograph cabinet having an opening in one wall thereof, of a drawer movable inwardly and outwardly of the opening of the cabinet, trackways extending inwardly at opposite sides of the opening and supporting said drawer, screw rods extending lengthwise of said drawer, a series of disk record holders extending transversely of the drawer and having openings engaging said screw rods, a follower plate actuated by said screw rods and adapted to support said holders in a normally inclined position rearwardly of said drawer, means for actuating said screw rods, and stops carried on said follower plate for limiting the outward movement of said drawer.

In testimony that I claim the foregoing I have hereunto set my hand at Columbus, in the county of Columbia and State of Wisconsin.

ROY J. MILLER.
